United States Patent Office

Des. 208,382
Patented Aug. 22, 1967

208,382

SAFETY REFLECTOR

Morris Rider, 436 W. Grand Blvd.,
Detroit, Mich. 48216

Continuation of design applications Ser. No. 2,487, May
31, 1966, and Ser. No. 2,783, June 23, 1966. This ap-
plication Dec. 22, 1966, Ser. No. 6,096

Term of patent 14 years

(Cl. D72—1)

FIG. 1

FIG. 3

FIG. 2

FIG. 4

FIG. 5

FIG. 6FIG. 8FIG. 7FIG. 10FIG. 9FIG. 1 is a front elevational view of a safety reflector illustrating a first form of my new design;

FIG. 2 is a rear elevational view thereof;

FIG. 3 is a right side view thereof, the left side being a mirror image of the right side shown;

FIG. 4 is a top view thereof;

FIG. 5 is a bottom view thereof;

FIG. 6 is a front elevational view of a safety reflector illustrating a modified form of my new design;

FIG. 7 is a rear elevational view of my modified design;

FIG. 8 is a right side view of my modified design, the left side being a mirror image of the right side shown;

FIG. 9 is a top view of my modified design; and,

FIG. 10 is a bottom view of my modified design.

This is a continuation of design application Ser. Nos. D.2,487 filed May 31, 1966 and D.2,783 filed June 23, 1966, both now abandoned.

I claim:

The ornamental design for a safety reflector, substantially as shown and described.
